CLAIM

The ornamental design for the fish handler, as shown and described.

DESCRIPTION

FIG. 1 is a perspective view of a fish handler showing my new design, and showing in phantom a fish supported thereon;

FIG. 2 is a top view of the fish handler shown in FIG. 1;

FIG. 3 is a front elevational view thereof;

FIG. 4 is a right side view thereof, the left side view being a mirror image thereof;

FIG. 5 is a back elevational view thereof; and,

FIG. 6 is a bottom view thereof.
